UNITED STATES PATENT OFFICE

2,140,890

WINDOW

Joseph J. Waitekaites, Stambaugh, Mich.

Application November 10, 1936, Serial No. 110,137

1 Claim. (Cl. 189—67)

The present invention relates to new and useful improvements in windows of the type including vertically slideable upper and lower sashes and has for one of its important objects to provide, in a manner as hereinafter set forth, a novel construction and arrangement through the medium of which said sashes may be expeditiously swung inwardly in a horizontal plane to facilitate washing of the outer surface of the glasses.

Another very important object of the invention is to provide a window of the aforementioned character wherein substantially the entire construction, such as the frame, upper and lower sashes, etc. are formed of sheet metal.

Still another very important object of the invention is to provide, in a window of the aforementioned character, novel means for locking the sashes in closed position.

Other objects of the invention are to provide a window of the character described which will be comparatively simple in construction, strong, durable, attractive in appearance, light in weight and which may be manufactured at low cost.

All of the foregoing and still further objects and advantages of the invention will become apparent from a study of the following specification, taken in connection with the accompanying drawings wherein like characters of reference designate corresponding parts throughout the several views, and wherein:

Figure 1 is an elevational view of the invention, looking at the inner side thereof.

Figure 2 is a vertical sectional view, taken substantially on the line 2—2 of Figure 1, looking in the direction indicated by the arrows.

Figure 3 is a vertical sectional view, taken substantially on the line 3—3 of Figure 1, looking in the direction indicated by the arrows.

Figure 4 is a view in horizontal section through the invention, taken substantially on the line 4—4 of Figure 1.

Figure 5 is a detail view in cross section through one of the sash rails.

Figure 6 is a fragmentary view in vertical section taken on the line 6—6 of Figure 4 looking in the direction indicated by the arrows and showing the manner in which the lower sash is suspended by the ropes and counterweights, and

Figure 7 is a similar view taken on the line 7—7 of Figure 4 looking in the same direction and illustrating the manner in which the upper sash is suspended.

Referring now to the drawings in detail, it will be seen that the embodiment of the inven-

tion which has been illustrated comprises a frame which is designated generally by the reference numeral 1, said frame being of hollow sheet metal construction. The frame 1 includes a sill 2, vertical side members 3 and a horizontal top member 4 extending between the upper ends of said side members 3.

One of the side members 3 and the cross member 4 of the frame 1 are formed to provide spaced, parallel guides 5, 6 and 7 which are adapted to receive therebetween upper and lower sashes 8 and 9, respectively. The sashes 8 and 9, it will be noted, are also of hollow sheet metal construction and mounted therein are panes of glass 10.

The vertical side member 3 of the frame 1 which is free of the guides 5, 6 and 7 has formed therein spaced, parallel channels 11 of arcuate cross section which extend from the sill 2 to the cross member 4. Adjacent the channels 11 vertical rods 12 of circular cross section extend between the sill 2 and the top cross member 4. The metallic sashes 8 and 9 are rotatably and slidably mounted on the rods 12 in a manner to permit said sashes to be raised and lowered in the frame 1 and swung inwardly from said frame in a horizontal plane, as suggested in dotted lines in Fig. 4 of the drawings. The pivoted side members of the sashes 8 and 9 are rounded to substantially conform to the channels 11 in which they are engaged.

Ropes 13 are secured to the pivoted sides of the sashes 8 and 9 and travel over grooved pulleys 14 which are provided therefor in the adjacent side member 3 of the frame 1. Counterweights 15 are connected to the other ends of the ropes 13 for vertical travel in the respective side member 3 of the frame 1 as the sashes are raised and lowered. The guides 5 and 6 on one of the side members 3 of the frame 1 comprise removable lower sections 16 which are secured in position by screws 17 or other suitable means.

The meeting rails 18 and 19 of the upper and lower sashes 8 and 9, respectively, have formed in their opposed faces openings which are brought into registry when the sashes are in closed position. Pivotal mounted in the meeting rail 19 of the sash 9 is a latch 20 which is engageable in the aforementioned registering openings for positively locking the sashes in closed position. This is shown to advantage in Figure 2 of the drawings. An operating rod 21 extends slidably into the meeting rail 19 of the lower sash 9 and is pivotally connected to the latch 20. A coil 55

spring 22 is provided for yieldingly urging the latch 20 toward operative or locking position.

Bayonet grooves or slots 23 are provided in the upper portions of the side members 3 of the frame 1 for receiving a curtain roller. The reference numerals 24 and 25 designate trim on the cross member 4 and the sill 2 of the frame 1. If desired, curtain fixtures (not shown) may be mounted on the trim 24. The panes 10 are secured in position in the sashes 8 and 9 through the medium of strips 26 and screws 27 (see Figure 5). The strips 26 are substantially triangular in cross section and said strips may be of any suitable material. Cushioning strips 28 are provided between the two sashes 8 and 9 and the panes 10.

With the latch 20 retracted against the tension of the coil spring 22 the upper and lower sashes 8 and 9, respectively, may be moved vertically in the frame 1 in the usual manner, said sashes traveling on the rods 12. When it is desired to wash the outer surfaces of the panes 10, the sections 16 of the guides 5 and 6 are removed. The lower sash 9 is then raised sufficiently to clear the stool 29 of the sill 2, after which said lower sash may be swung inwardly in a horizontal plane, as shown in dotted lines in Figure 4 of the drawings. The upper sash 8 may then be lowered and swung inwardly in a

similar manner. As shown to advantage in Figure 4 of the drawings, the pivoted sides of the sashes 8 and 9 are formed to provide recesses 30 which accommodate the ropes 13.

It is believed that the many advantages of a window constructed in accordance with the present invention will be readily understood, and although a preferred embodiment of said window is as illustrated and described, it is to be understood that changes in the details of construction and in the combination and arrangement of parts may be resorted to which will fall within the scope of the invention as claimed.

What is claimed is:—

A window of the class described comprising a hollow sheet metal frame including spaced guides, said guides comprising removable sections, vertical rods of circular cross section mounted in the frame adjacent one side thereof, said one side of the frame having spaced, parallel depressed portions forming channels therein of arcuate cross-section, hollow sheet metal sashes mounted for sliding and swinging movement on the rods, one side of said sashes being substantially rounded for engagement in the channels, said sashes being adapted to swing in a horizontal plane on the rods when the removable guide sections are detached from the frame.

JOSEPH J. WAITEKAITES.
